UNITED STATES PATENT OFFICE.

RICHARD A. SHANNON, OF PHILADELPHIA, PENNSYLVANIA, ASSIGNOR OF ONE-
THIRD TO JOHN M. VARBLE, OF FREEDOM, PENNSYLVANIA, AND ONE-THIRD
TO SHERIDAN E. SNYDER, OF NEW BRIGHTON, PENNSYLVANIA.

ELECTRICAL APPARATUS FOR CONTROLLING AND CLASSIFYING CARS.

1,360,150.

Specification of Letters Patent. Patented Nov. 23, 1920.

Application filed April 17, 1920. Serial No. 374,667.

To all whom it may concern:

Be it known that I, RICHARD A. SHANNON, a citizen of the United States, residing at Philadelphia, in the county of Philadelphia and State of Pennsylvania, have invented new and useful Improvements in Electrical Apparatus for Controlling and Classifying Cars, of which the following is a specification.

10 This invention relates to car handling means, and more particularly to means for controlling and classifying freight cars.

One of the main objects of the invention is to provide simple and efficient means whereby freight cars may be readily controlled and classified, and danger of wrecks due to one car running into another may be avoided. A further object is to provide means whereby the rate of travel of the cars upon a track, 20 and their relative positions may be readily determined. A further object is to provide simple and efficient means for retarding the travel of any car, selectively, upon the track. Further objects will appear from the detailed description.

In the drawings:—

Figure 1 is a diagrammatic view of a car controlling means constructed in accordance with my invention.

30 Fig. 2 is a fragmentary side view of the track.

Fig. 3 is a detail of one of the control magnets and associated parts.

Fig. 4 is a detail of one of the contacts 35 and associated parts.

At present it is the practice in freight yards to classify the cars according to their contents by pushing the same down an incline or "hump" on to a main or "ladder" 40 track with which a plurality of spurs communicate, men being stationed at each spur to direct the car on to the proper spur or side track. It frequently happens that a car is given such a push as it starts down the 45 hump that it overtakes and runs into a preceding car thus causing a wreck. It is the primary object of my invention to provide simple and efficient means whereby the travel 50 of the cars upon the main or ladder track and the spurs may be observed and readily controlled so as to eliminate danger of these

wrecks. In Fig. 2 of the drawing I have shown a track having an approach 1 from which extends an incline 2 leading to the main or ladder track 3. Spurs 4, 5, 6, and 7 55 communicate with this main track in the known manner.

A control board 8 is placed in any suitable position, and this board is provided with a plurality of rows 3^a, 4^a, 5^a, 6^a, and 7^a of 60 electric lights 9, these rows corresponding to the main track and the spurs. The lights of the upper row 3^a have one side connected by a wire 10 to a battery 11, or other suitable source of supply of electrical energy, 65 the other side of which is connected by a wire 12 to one rail 13 of track 3. The other side of each light is connected by a wire 14 to a resilient contact member 15 which is positioned adjacent to the inner face of the 70 tread of rail 13, this contact being so placed as to contact with the flange of a wheel 16 of a car traveling upon the track. As will be understood, there is a plurality of these contacts disposed in spaced relation to the rail 75 along the track, and these contacts serve to successively illuminate the lights 9 so as to indicate the rate of travel and the position of a car upon the track. At intervals along the track, I provide electro-magnets 17, the 80 casing of each of these magnets being of soft iron and positioned adjacent to the rail of the track and shaped to receive the flange of a car wheel 16 traveling upon the track. One side of the coils of each of these magnets 85 is connected by a wire 18 to the jaw 19 of a control switch mounted upon the board 8, the blade of this switch being connected by a wire 20 to one side of an electric battery 21 the other side of which is connected by a wire 90 22 to the other side of the coils of the magnet. The switches for the different electro-magnets are mounted upon the board in the same relation to the lights 9 as the electro-magnets bear to the contacts 15. As will be 95 readily understood, an operator standing before the board 8 can readily follow the travel of a car upon the track 3. In the event that one car appears to be overtaking a car in advance of it, by throwing the switch immediately in advance of the lights illuminated by the rear car, he can readily check the travel 100

of this car so as to prevent it from running into the front car. In practice, the lights of the different series will be connected up to the spurs in the same manner as the lights 5 of series 3^a are connected to the main track, and the electro-magnets of these spurs will also be connected to control switches upon the board 8 in the same manner as electro-magnets 17 are connected. To avoid confusion 10 the connections for the lights and electro-magnets of the spurs, and some of the lights and electro-magnets of the main track, have been omitted in Fig. 1 of the drawings, but it will be understood that these connections 15 will be inserted in practice.

What I claim is:

1. In car classifying means, a track, a control board, a series of lights arranged in a row on the board, a source of electrical energy having one side connected to one side of the lights and its other side connected to one of the rails of the track, a plurality of contacts mounted adjacent to said rail and adapted to contact with the wheels of a car 25 traveling upon said track, said contacts being connected to the other side of the lights in order to indicate the position and rate of travel of the car, electro-magnets arranged adjacent to the rails of the track at intervals, 30 and control switches for said magnets arranged on the board in the same relation to the lights as the magnets bear to said contacts.

2. In-car classifying means, a track, a control board, a series of lights arranged in a row on the board, a source of electrical energy having one side connected to one side of the lights and its other side connected to one of the rails of the track, a plurality of 35 contacts mounted adjacent said rail and adapted to contact with the wheels of a car traveling upon said track, said contacts being connected to the other side of the lights in order to indicate the position and rate of 40 travel of the car, electro-magnets arranged adjacent the rails of the track at intervals and adapted to receive the flange of the car 45 wheels, and control switches for said magnets arranged on the board in the same relation

to the lights as the magnets bear to said contacts. 50

3. In car classifying means, a track, a control board, a horizontal row of lights mounted on the board, a source of electrical energy having one side connected to one side 55 of said lights and its other side connected to one of the rails of the track, a plurality of contacts mounted adjacent to said rail and spaced apart longitudinally thereof, said contacts being adapted for contact with the 60 wheels of a car traveling upon said track and being connected to the other side of said lights to indicate the position and rate of travel of the car, electro-magnets positioned at intervals adjacent to the track rails and 65 adapted to receive the flange of the car wheels, and control switches for the respective magnets mounted on the board and in the row of lights, the position of the switches relative to the lights corresponding 70 to the relative positions of the contacts and magnets on the track.

4. In car classifying means, in combination with a main track and a ladder track, 75 said main track including a portion inclined downwardly toward the ladder track, a control board, a series of rows of lights mounted on said board, a source of supply of electrical energy having one side connected to the lights and its other side connected to 80 one rail of the main and ladder tracks, spaced contacts positioned adjacent to the said rail and connected to the other side of the lights, electro-magnets positioned adjacent to the rails of the main and ladder 85 tracks, and control switches for said magnets interposed in the rows of lights, the lights and switches of the different rows being connected to the contacts and magnets of the respective tracks and arranged in the 90 same relation as said contacts and magnets, the rows of lights being arranged on the board in the same relation to each other as the main track and the ladder track bear to each other. 95

In testimony whereof I affix my signature.

RICHARD A. SHANNON.
